CLAIM

The ornamental design for a combined mudguard and light support for trucks, as shown.

DESCRIPTION

FIG. 1 is a front elevational view of a combined mudguard and light support for trucks showing my new design;

FIG. 2 is a top plan view thereof;

FIG. 3 is a right side elevational view thereof, the left side being a mirror image of the right shown herein; and
FIG. 4 is a rear elevational view thereof.

FIG. 4
